ENGINE CONTROL MEANS

Robert I. Dick, Beloit, Wis., assignor to Fairbanks, Morse & Co., Chicago, Ill., a corporation of Illinois

Application December 18, 1936, Serial No. 116,501

9 Claims. (Cl. 74—479)

This invention relates to improvements in engine control means, and more particularly to an improved control mechanism for use with two or more engines, adapted selectively, to provide for a unified or concurrent control of the engines, or for an independent control of each thereof.

The control mechanism embodying the novel features of this invention, is particularly suited for well drilling rigs and the like, wherein a plurality of engines are utilized in the well drilling operations, as in the instance of oil well drilling where one of the engines may be used for the drilling operation and another for operating the slush pumps. In such case and particularly where internal combustion engines of the Diesel type are employed, according to the now prevailing practice, a ready and facile control of engine speed must be provided, so that during certain stages of the well drilling process, the engine speeds may be regulated and controlled either concurrently or separately, according to the demand therefor. Moreover, it is most desirable under the presently prevailing well drilling requirements, to provide a control mechanism which may be readily operated from a single control station, located either adjacent to or remotely from the engines and drilling equipment.

Accordingly, an object of this invention is to provide an efficient and positive engine control mechanism in operative association with the speed governor organizations of the engines, adapted for regulating the engine governors to control the engine speeds, and to provide a control which attains selectively, either a unified speed control of all the engines utilized, or a separate and independent speed control of the engines, and further, in which the manipulative elements of the control mechanism may be located at a control station remote from the engines.

Another object of the invention is to provide, in operative association with the improved control mechanism of the general character described, means for selectively regulating the slow speed control setting of the mechanism.

Another object is attained in the provision of a control for the engine power transmission mechanism actuated by an operating element of the engine speed control mechanism, the actuation of the transmission control being effected by the speed control operating element without such operating element affecting the speed control.

A further object is found in the provision of an improved engine speed control mechanism of the character described, which is comprised of but few parts, arranged and assembled in a manner to provide a positive regulation of engine speed.

Further objects and advantages will appear from the following description, and from the drawing, in which:

Fig. 1 is a longitudinal assembly elevation of a pair of internal combustion engines illustrating the improved control mechanism of this invention, in operative assembly with the engines; Fig. 2 is an assembly plan view of the arrangement of Fig. 1; Fig. 3 is an enlarged transverse elevation partly in section, of a part of the organization of Fig. 1, as viewed from line 3—3 therein; Fig. 4 is an enlarged side elevation of a portion of the organization of Figs. 1 and 2, as viewed from line 4—4 of Fig. 2; Fig. 5 is a fragmentary sectional elevation of the control mechanism, as viewed from line 5—5 in Fig. 4; Fig. 6 is an enlarged side elevation of a portion of the organization of Figs. 1 and 2, as viewed from line 6—6 in Fig. 2; Fig. 7 illustrates in side elevation, a modification of that part of the control mechanism shown in Fig. 5; Fig. 8 is an end elevation of the modified structure, as viewed from line 8—8 in Fig. 7; Fig. 9 illustrates a further modified structure forming a part of the improved control mechanism, the view showing portions thereof in section for the purpose of better illustrating certain features of the structure; Figs. 10, 11, 12 and 13 are enlarged transverse sections of the structure, as taken respectively, along lines 10—10, 11—11, 12—12, and 13—13 in Fig. 9, and Fig. 14 is an enlarged longitudinal section of a portion of the modified structure, as taken along line 14—14 in Fig. 9.

Referring to the drawings by suitable characters of reference, there is shown in Figs. 1 and 2 a pair of internal combustion engines 10 and 11, arranged in substantially end-to-end relation with their driving sprockets or pulleys 12 and 13 respectively, adjacently disposed. For purposes of illustration, the engines 10 and 11, which are preferably of the Diesel type, may form the power units of an oil well drilling rig, in which case one of the engines, say 10, may be utilized for the drilling operations, while engine 11 may operate the mud and slush pumps. Each engine may be mounted on its own foundation structure, or both secured upon a common foundation, as desired. In the present example, each engine is

shown as mounted upon a pair of I-beams 14 extending longitudinally of the engine.

As will be readily understood by those familiar with the well drilling art and with drilling rigs utilizing a plurality of engine units, one for the drilling operations and another for operating the well pumps, that it is desirable during certain stages of the drilling process, to regulate the speed of the pump operating engines independently of the speed control of the drilling engine, and at other times, to regulate the speed of both engines simultaneously. Accordingly, the purpose of this invention as above noted, is to provide an engine speed control capable of attaining selectively, a separate or unified regulation of engine speeds. To this end is provided the improved control mechanism now to be described.

The engines 10 and 11 are provided respectively, with speed governor organizations denoted generally by the numerals 16 and 17, the governors being of any suitable type and provided respectively, with regulating arms 18 and 19 with which the control mechanism of this invention functions to regulate the speed of the engines.

A supporting frame for a part of the control mechanism is carried by the I-beams 14, supporting one of the engines, in the present illustration by those supporting the engine 10. The frame as clearly appears in Fig. 3, is essentially a pair of upright elements 20, and a horizontally arranged member 22 extending transversely of the engine and supported upon the elements 20 in any suitable manner. A bearing element 23 is secured upon one end 24 of the member 22, while a similar bearing element 25 is likewise secured to the opposite end 26 of the member. A control shaft 28 has its end portions 29 and 30 journaled respectively, in the bearings 23 and 25, with the shaft end 30 extended outwardly beyond the bearing 25 (Figs. 3 and 5) to serve as an operative support for certain of the control elements now to be described.

Disposed at a control station located either adjacently to the engine organization, or remotely therefrom, is a main control shaft 31 having its ends journaled in spaced supports 32. As shown, these supports are by preference, secured upon I-beam sections 34, although they may be mounted in any other suitable manner. To one end of the shaft 31 is secured a manually controlled, shaft operating element or hand wheel 35, and to the opposite end of the shaft is secured a gear or sprocket element 36. Engaging sprocket 36 is a drive chain 37 which operatively connects the shaft 31 and sprocket 36 to a sprocket 38 carried by the end 30 of control shaft 28, sprocket 38 being secured to the shaft end 30 by means of a suitable key 40 (Fig. 5). Thus control manipulation of the hand wheel 35 serves to rotate its shaft 31, and through the described sprocket and chain drive connection, to rotate the control shaft 28.

Rotation of control shaft 28 is utilized to actuate the regulating arm 18 of governor 16 associated with engine 10, the manner of connecting arm 18 to shaft 28 best appearing in Figs. 3 and 6. To the end portion 29 of shaft 28 is secured a crank arm 41, the free end 42 of which may be furcated as shown, to receive between the furcate elements 43, one end 44 of a member 46, the crank arm and member being pivotally connected by a suitable pivot pin 47 seated in the furcate elements 43. The opposite end of the member 46 is, by preference, expanded and provided with a threaded, axial bore 48 to receive the

threaded end 49 of a tie-rod 50. The rod 50 is extended toward the governor 16 and has its end 52 pivotally connected to the governor regulating arm 18 through a link element 53, one end 54 of which engages the end 52 of rod 50, with its opposite end 55 pivotally connected to the free end 56 of governor arm 18 by a pin 58. The rod end 52 is threaded as shown, to receive a pair of securing nuts 59 located on opposite sides of the link end 54, these nuts serving to permit adjustment of the link end 54 along the rod end 52 and to maintain the link and rod in assembly and in adjusted relation. Moreover, by reason of the described adjustable connection of the rod end 52 and link 53, and the threaded engagement of the rod end 49 and member 46, the operative length of the cooperating rod and member may be adjusted as required.

From the foregoing description of the control arrangement, it will be readily observed that by actuating the control wheel 35 to rotate its shaft 31, shaft 28 will be rotated, through the heretofore described sprocket and chain drive connection therebetween, rotation of shaft 28 being transmitted to the governor regulating arm 18 through the described linkage system. Hence, a control of the governor 16 to regulate the speed of engine 10, is readily attained through manipulation of the hand wheel 35.

As a means for yieldably maintaining the shaft 28 in any adjusted position, as determined by the actuation of control wheel 35, a finger element 60 is provided, having a hub 61 seated on the shaft end 30 and secured thereto, as by a key 62. The free end portion of the finger is axially bored 35 as at 64 to receive a plunger element 65 and a spring 66, the spring serving to urge the plunger outwardly of the bore 64 and into yieldable locking engagement with the teeth of a ratchet segment 67, in the manner shown in Figs. 4 and 5. Segment 67 may be carried by and formed as a part of the shaft bearing element 25, as preferred and illustrated in Fig. 5.

Movement of shaft 28 under the control of hand wheel 35, while providing for the regulation of governor 16 on engine 10, may be utilized also for regulating the governor mechanism 17 associated with engine 11, to provide a unified and concurrent regulation of the engine speed of both engines 10 and 11. In attaining this end, an arm or pitman 68 may be provided on the hub 61 of finger element 60, the arm preferably being formed as an integral part of the hub. The free end of the arm is of bifurcate form as shown, and seated between the furcate elements 70 thereof, is one end 71 of a member or bar 72, the bar end being pivotally connected to the furcate elements through a pivot pin 73. The pivotal connection of the bar 72 to the pitman furcate elements is, by preference, made in a manner to permit a ready removal of the pin 73 so as to effect a disconnection of bar 72 from pitman 68, for a purpose which will later appear.

The bar 72 is operatively connected to the regulating arm 19 of governor 17 associated with engine 11, through a rod 74 and a link element 76, the link having one end 77 pivotally connected to the governor arm 19 through a pin connection 78 and its opposite end adjustably connected to the end 79 of rod 74, as by the adjustable securing nuts 80. The end 82 of rod 74 threadedly engages the end 83 of bar 72, as shown in Fig. 4. Through the threaded connection of bar 72 and rod 74, and the adjustable connection of the link 76 to rod 74, the effective length 75

of the operative connection between the pitman 68 and governor regulating arm 19 may be varied for adjustment purposes.

It will be readily observed from the description of the control mechanism thus far, that a simultaneous regulation of the speed of both engines may be readily attained by rotation of control shaft 28, through manipulation of the main control wheel 35. It will be observed also, that by removing the pin 73 so as to disconnect the bar 72 from the pitman 68, actuation of wheel 35 to rotate shaft 28 will effect a direct control of the governor 16 to regulate the speed of engine 10, independently of any regulation of engine 11. Thus the described control mechanism may be utilized either for an independent regulation of the speed of engine 10, or for a concurrent control of the speed of both engines 10 and 11, the latter control depending upon the connection of bar 72 to the pitman 68.

In order to effect an independent speed regulation of the engine 11, an auxiliary control mechanism is provided in the presently improved control system. The auxiliary control comprises an operating shaft 86 preferably disposed parallel to shaft 31 and with its ends journaled in the supports 32. One end of shaft 86 carries an operating wheel 87, while the opposite shaft end carries a sprocket 88. A sprocket 89 is carried by and is free to rotate on the end 30 of shaft 28, the sprocket 89 being operatively connected with the sprocket 88 by a chain 90, as shown in Figs. 3 and 5. For convenience in maintaining the sprocket 89 on the shaft end 30, the sprocket is located between the sprocket 88 and the finger and pitman structure 60-68, and to the hub 92 of sprocket 89 is secured a pitman or arm 93. In the present example, it is preferred to provide the pitman 93 as an integral part of the hub 92. The pitman 93 is formed similarly to the pitman 68, being provided with furcate elements 94 for the reception therebetween, of the end 71 of bar 72, and to which the bar end 71 may be pivotally connected, as by the pin 73 heretofore noted in the connection of the bar 72 to the pitman 68. Thus, with bar 72 pinned to the pitman 93, the auxiliary control wheel 87 may be operated to regulate the governor mechanism 17 associated with engine 11, independently of any regulation of governor 16 on engine 10, as effected through the main control wheel 35.

From the foregoing, it will be readily observed that when the bar 72 is pinned to the pitman 68, both engine governors 16 and 17 may be regulated simultaneously, through actuation of the main control wheel 35. With bar 72 disconnected from pitman 68 and pinned to pitman 93, the auxiliary control wheel 87 may be utilized to effect an independent regulation of governor 17 on engine 11, while main control wheel 35 is operable to effect an independent regulation of governor 16 on engine 10. Accordingly, the selective connection of the bar 72 to either pitman 68 or 93 pre-conditions the control mechanism for concurrent or independent regulation of the engine governors, in determining engine speeds.

While the selective connection of the bar 72 to the main and auxiliary controls of the present system, is made through the pinning of the bar 70 to one or the other of the pitmans 68 and 93, the same result may be attained through the use of a suitable clutch mechanism, with the clutch arranged to be controlled from the location of the control wheels 35 and 87. A clutch arrangement suitable for this purpose is exemplified in Figs.

7 and 8, the clutch mechanism being, by preference, of a well known type and comprising a clutch element 95 slidable longitudinally of the shaft end 30 and operatively secured thereto through a key or spline 96. Clutch element 95 carries a plurality of projections or dogs 98 on a lateral face thereof, adapted to seat in cooperating recesses 99 provided in a lateral face of the hub of sprocket 89, when the clutch element is moved toward the sprocket. The clutch element 95 may be actuated along shaft end 30 by the manipulation of a pivoted yoke element 100 pivotally supporting a member 101 engaging a peripheral groove 102 formed in the clutch member. The yoke may be pivotally mounted at 104 upon a pin 105 carried by a supporting arm 106, the arm 106 being, by preference, formed as a part of the bearing structure 107 for the shaft end 30. Extending from the yoke portion 104 is a yoke operating arm 108, to the outer end 110 of which is connected one end of a lever system denoted generally by the numeral 111, and shown in dotted lines in Fig. 3, the lever system operatively associating the yoke and clutch with a clutch actuating member 112 (Fig. 3) located adjacent the engine speed control wheels 35 and 37. It is noted in this instance, that the bar 72 may be permanently pinned to the pitman 93 carried by sprocket 89, thus eliminating any need for the pitman 68 shown in Fig. 5.

The operation of the clutch controlled system is such that when it is desired to control the engine governors simultaneously, through the main control wheel 35, the clutch actuating member 112 is operated in a manner to effect an engagement of the clutch element 95 with the sprocket 89, thus to operatively connect the sprocket 89, pitman 93 and the regulating arm 19 of engine governor 17 through bar 72, to the control shaft 28. When an independent control of the engine governors is desired, the member 112 is actuated to effect a disengagement of the clutch from sprocket 89, thus permitting an independent control of governor 17 through the auxiliary control wheel 87, as heretofore described, and a like independent control of governor 16 through main control wheel 35 and associated operating elements. Since the clutch actuating member 112 is disposed adjacent the control wheels 35 and 87, the selective speed regulation of the engines 50 provided by the improved control system of this invention, may be effected entirely from a single control station, as shown in Fig. 3, located either adjacently to or remotely from the engines to be controlled.

The engine speed control apparatus is hereinabove described in connection with two Diesel engines which constitute the prime movers of a well drilling rig. In addition to the speed control means which operate on the engine governors, means are usually provided for reversing the direction of operation of the drilling rig, and such means commonly comprise a gear box or other suitable transmission assembly disposed in driving line between the engines and the drilling rig. Such transmission assembly is not shown in the accompanying drawings, but the link or control rod between such transmission and the regulating mechanism which forms the subject of the present invention, is indicated at 136 on Fig. 9.

Where it is desired to regulate the engine power transmission from the engine speed control station, this may be accomplished either by a separate control therefor, operable from the

control station, or in the preferred manner illustrated in Fig. 9. Considering the control arrangement of Fig. 9, the structure there illustrated is substituted for the main control shaft 5 shown in Fig. 3, and is essentially a modification thereof. The modified structure comprises a shaft element 115 of square section, having a round end portion 116 journaled in a support 117 and extending outwardly therefrom. Operatively secured to the extended portion 116, as by a suitable key 118, is a sprocket 119 engaging the chain 37 shown in Fig. 3. In order to prevent axial displacement of the shaft section 115, the shaft is retained in position by a collar 120 and the sprocket 119, in the manner shown. The remainder of the shaft structure comprises one or more sections, two being shown in Fig. 9 and designated by the numerals 122 and 123, the sections being connected by a coupling element 124. The section 122 is journaled in a support 125 in a manner to permit axial sliding movement of the section, and carries on its free end 126 an operating element or hand wheel 127. The section 123 is of tubular form, and extending within this section is the square shaft section 115, the shaft 115 being constrained to follow the rotary movement of the tubular section by a plurality of elements 128 arranged in spaced relation within the tubular section and secured to the section in any suitable manner. Each of the elements 128 is provided with a square axial opening 129 to receive the square shaft 115, these elements forming a coupling between the shaft and tubular section for rotary movement and at the same time serving to permit relative axial movement therebetween.

Sleeved on the tubular section 123 is a transmission control element 130 provided with a laterally extending arm 132, the arm being bifurcated as shown at 133, to receive between the furcate elements 134, one end 135 of the control rod 136, the rod end 135 being pivotally connected to the furcate elements by a suitable pivot pin 137. The control rod 136 extends to the transmission mechanism (not shown) for control thereof, with the actuation of the control effected in the following manner.

The element 130 is constrained to follow axial movements of the section 123 by collars 138 arranged on opposite sides of the element and secured to the section by suitable clamping bolts 139. With this arrangement of the transmission control element, the tubular section may be rotated to effect a speed control of the engines 50 without affecting the transmission control, the speed control of course being effected by rotating the shaft structure and sprocket 119 to drive the chain 37 which in turn, operates the control mechanism associated with the engine governors 55 in the manner heretofore described. Similarly, by axially shifting the sections 122 and 123, the elements 130 and 136 will be actuated to effect a control of the transmission mechanism, this latter control being attainable without affecting 60 the engine speed control, by reason of the sliding connection between the tubular section 123 and the speed control shaft 115.

Suitably located on the shaft section 122 on opposite sides of the support 125, are stop elements or collars 140 and 142, these elements being clamped upon the section by clamping bolts 143. The stop elements determine the control settings of the transmission control, as for forward and reverse drive. For example, displacing 70 the shaft section to the left of Fig. 9, as by

pulling the hand wheel 127 to the left until the stop element 140 abuts the support 125, determines the reverse drive condition of the transmission, while displacing the sections in the opposite direction until stop 142 engages the support 125, determines the forward drive of the transmission. Provision is made also for indicating the neutral position of the transmission, this being effected through a peripheral groove 144 formed in the section 122 between the stops 140 and 142. Cooperating with the groove is a plunger element 145 which is urged laterally toward the section 122 by a suitable spring 146, the plunger and spring being by preference, seated in an aperture or bore formed in a portion of the support 125, and retained therein by a plug 147, as clearly shown in Fig. 9. Thus, when the plunger seats in the groove, this indicates to the operator the neutral position of the transmission. The neutral indication is attained, as 20 will be readily understood, from the increased effort required on the part of the operator, to displace the shaft section from the position in which the plunger engages the groove. In this connection, to permit the shaft section 122 to be 25 displaced by the plunger without too great effort, the side faces of both the groove and plunger may be sloped or beveled to provide camming surfaces.

A further feature of the presently improved 30 engine speed control mechanism is found in a novel means for selectively limiting the actuation of the control in the direction to reduce engine speed. The control limiting means may be associated with either or both of the control shafts 31 and 86 of the arrangement shown by Fig. 3, or it may be associated with the control structure shown by Fig. 9. In the present example, it is preferred to illustrate and describe the limiting means in connection with the modified control structure of Fig. 9, as a matter of convenience, and also, to illustrate the operability of the means independently of axial displacement of the shaft structure for transmission control.

The details of the limiting means are clearly 45 shown in Figs. 9 and 12 through 14. As shown, a flanged sleeve 148 is seated on the shaft section 122 with its flanged end 149 adjacent the shaft support 125. The sleeve is connected to the shaft through a key 150 engaging a key slot 50 152 formed in the shaft and extending between the stop elements 140 and 142 so as to permit axial displacement of the shaft without affecting the connection of the sleeve thereto. The sleeve is retained in fixed position by a flanged collar 55 153 engaging the sleeve flange 149 and secured to the support 125 by suitable screws 154. Seated on the sleeve is a split collar 155, the ends 156 of the collar adjacent the split 157 being extended outwardly to receive a clamping bolt 158 for 60 securing the collar to the sleeve in any angular position thereon. A stop member 159 is pivotally mounted on a pin 160 carried by a bracket 162 extending from the shaft support 125, in the manner shown in Fig. 9. The free end 163 of 65 the stop is adapted for engagement with a side face 164 of one of the projecting ends 156 of the split collar, thus limiting the control movement of the shaft section 122 and associated control elements. A handle 165 is associated 70 with the stop element for enabling the operator to pivot the stop out of alignment with the face 164 of the split collar, this being done when it is desired to rotate the control shaft and collar beyond the stop.

Fig. 13 illustrates diagrammatically, the angular extent of control movement of the shaft structure, beginning at the engine stop position indicated at 166 and extending in a counter-clockwise direction through the slow speed position indicated at 167, to the fast speed position indicated at 168. The angular position of the collar 155 on the sleeve 143 is adjusted so that during normal operation of the engines, the speed control may be operated only between the fast speed position 168 and the slow speed position 167, movement of the control shaft 122 toward the slow position being effectively limited through the engagement of the collar projection 156 with the stop member 159. When it is desired to stop the engines for any purpose, the operator may actuate the handle 165 to swing the stop out of alignment with the collar projection 156, thus permitting angular movement of the control shaft to the stop position 166. The provision of the stop device assures against overrunning the slow speed position during the normal regulation of engine speed between fast and slow, so as to prevent stalling or premature stopping of the engines.

It will be observed in Fig. 13, that the angular extent of control movement of the shaft section 122 is such that the key 150 seated in keyway 152, does not contact the spring-pressed plunger 145 heretofore described, thus there is no interference between these elements throughout the control actuation of the mechanism.

It is to be understood that the invention is not to be limited to the particular embodiments thereof illustrated and described herein, but that alterations and modifications may be made in the structure and arrangement of parts without departing from the spirit and scope of the invention, as defined by the appended claims.

I claim:

1. In combination with a plurality of internal combustion engines each provided with a speed governor, control means for one of said governors, operable at a distance from said engines, control means for a second governor, including a rotatable member, an actuating element connectible between said member and second governor and operating means for said member, operable remotely from said engines, and means adapted for selectively connecting said first control means to said actuating element for concurrent control of said governors.

2. In combination with a plurality of internal combustion engines each provided with speed regulating means, control means for one of said regulating means, including a control shaft and shaft-operating means operable remotely from said engines, control means for a second speed regulating means including a member rotatable on said control shaft, an actuating element for said second speed regulating means connectible to said member and mechanism for operating said member remotely from said engines, and means adapted for operating said actuating element from said control shaft for concurrent control of said regulating means.

3. In combination with a plurality of internal combustion engines each provided with speed regulating means, a control shaft operatively associated with one of said speed regulating means, a pair of control elements disposed at a distance from said engines, an operative connection between said shaft and one of said control elements, an arm pivoted upon said control shaft, a second arm secured to said shaft, an

operative connection between said pivoted arm and the other of said control elements, and means operatively associated with another of said speed regulating means, adapted for selective connection to either of said arms.

4. In combination with a plurality of internal combustion engines each provided with speed regulating means, a control shaft operatively associated with one of said speed regulating means, a plurality of control elements located at a distance from said engines, an operative connection between said shaft and one of said control elements, a member pivoted upon said shaft, an operative connection between said member and a second control element, means connecting said member and another of said speed regulating means, mechanism carried by said control shaft and operable selectively, to connect said member to the shaft, and an operative connection between said mechanism and a third control element.

5. In combination with a plurality of internal combustion engines each having speed regulating means, control means for one of said regulating means, including a control shaft operatively associated with the regulating means, shaft actuating means operable at a distance from the engines, means yieldably maintaining the shaft in any control position, an independent control for a second speed regulating means including an actuating element, and means adapted for selectively operating said actuating element from said control shaft for concurrent control of said speed regulating means.

6. In combination with a plurality of internal combustion engines each provided with speed regulating means, control mechanism for one of said regulating means, including a control shaft, means operatively connecting the shaft to said regulating means, a second control shaft located remotely from the engines, sprockets on said shafts, a chain operatively connecting said sprockets, an operating element on said second shaft, control mechanism for another of said speed regulating means, and means adapted for the selective connection of said second speed regulating means to said second control mechanism for control thereby, or to said first control shaft for control thereof by said first control mechanism.

7. In combination with a plurality of internal combustion engines each provided with speed regulating means, control mechanism for one of said regulating means, including a control shaft, means operatively connecting the shaft to said regulating means, a second control shaft located remotely from the engines, sprockets on said shafts, a chain operatively connecting said sprockets, an operating element on said second shaft, control mechanism for another of said speed regulating means, including an arm mounted upon and freely rotatable about said first control shaft, a second arm operatively connected to said first control shaft, and means operatively associated with said second speed regulating means, adapted selectively, for connection to either of said arms.

8. In combination with a plurality of internal combustion engines each provided with speed regulating means, control mechanism for one of said regulating means, including a control shaft, means operatively connecting the shaft to said regulating means, a second control shaft located remotely from the engines, sprockets on said shafts, a chain operating on said sprock-

- sets, an operating element on said second shaft, control mechanism for another of said speed regulating means, including an arm mounted upon and normally freely rotatable about said first control shaft, a connection from said arm to said second speed regulating means, and means operatively associated with said first control shaft, for selectively connecting said arm to said first control shaft.
- 10 9. In combination with a plurality of internal combustion engines each having speed regulating means, control mechanism for one of said regulating means, including a control shaft operatively connected to the regulating means, a

second control shaft located remotely from the engines, means operatively connecting said shafts, control mechanism for another of said speed regulating means, including an operating element having a sprocket thereon, a sprocket 5 freely rotatable on said first control shaft, a chain connecting said sprockets, an arm carried by one of said sprockets, a second arm secured to said first control shaft, and means operatively associated with said second speed regulating 10 means, adapted for selective connection to either of said arms.

ROBERT I. DICK.
